UNITED STATES PATENT OFFICE.

WILLIAM V. OSBORNE, OF RACINE, WISCONSIN.

RAIL-ANCHOR.

1,129,004.

Specification of Letters Patent. Patented Feb. 16, 1915.

Application filed June 1, 1914. Serial No. 842,017.

To all whom it may concern:

Be it known that I, WILLIAM V. OSBORNE, a citizen of the United States, residing at Racine, in the county of Racine and State 5 of Wisconsin, have invented a certain new and useful Improvement in Rail-Anchors, of which the following is a full, clear, concise, and exact description, reference being had to the accompanying drawings, forming 10 ing a part of this specification.

My invention relates to rail anchors or anti-creeping devices, and the object of my invention is to provide a device of this class that may be easily and cheaply manufactured and one that may be readily applied 15 to a rail by an unskilled workman.

The embodiment of my invention herein described and subsequently claimed consists of a casting comprising a body portion arranged 20 to lie on the under side of the base of an associated rail, and formed integral with the body portion of the anchor is a clip arranged to embrace one edge of the base flange of the rail. The body portion of the 25 rail anchor has also formed integral therewith a portion arranged to receive a wedge of peculiar conformation, this wedge adapted to embrace the said rail on the edge thereof opposite the clip heretofore mentioned, 30 and arranged to lock the base of the rail anchor and parts carried thereby with respect to the rail. Also formed integral with the aforesaid body of the anchor is a downwardly-projecting arm or flange arranged to 35 bear against a tie with which the rail is associated to prevent the rail from creeping with respect to the tie.

In the accompanying drawings illustrating 40 my invention—Figure 1 is a view in perspective of my rail anchor complete; Fig. 2 is an elevational view illustrating my rail anchor in association with a rail and tie; Fig. 3 is a view in perspective of the wedge forming a part of my invention, and Fig. 45 4 is an end elevational view of the wedge shown in Fig. 3.

Similar reference numerals refer to similar parts throughout the several figures.

Referring first to Fig. 1, it will be seen 50 that the rail anchor of my invention comprises a casting forming a body portion 10 arranged to lie under the base of an asso-

ciated rail, and formed integral with the body portion 10 is a downwardly-extending projection 11 arranged to abut against the 55 side of a tie, as is clearly illustrated in Fig. 2. Formed integral with the body portion 10 is a clip 12 conformed and adapted to embrace one edge of the base of the rail with which the anchor is associated, and this clip 60 may be provided with reinforcing ribs 13, 18, as illustrated.

The body portion 10 of the rail anchor is enlarged at 14 to form a receptacle 15 arranged to receive a tapered wedge 16, illustrated in full lines in Figs. 3 and 4 and in dotted lines in Fig. 1. The walls of the receptacle 15 are preferably reinforced by integral ribs 17, 17, as illustrated. As is clearly shown in Fig. 1 of the drawings, the 70 walls of the receptacle 15 converge away from the tie-engaging portion 11 of the anchor, and the outer surfaces of the wedge 16 converge toward the tie-engaging portion 11 of the anchor when the wedge is in the position illustrated in dotted lines in Fig. 1.

The wedge 16 is longitudinally bifurcated at 18, and is adapted to be driven upon the edge of the rail flange opposite the edge embraced by the clip 12. The tapered wedge 80 may be said to be of substantially U-shaped cross-section, and the distance between the arms thereof is preferably less than the thickness of the base of the rail which it is designed to engage, so that when the wedge 85 is driven upon the rail base, the tendency of the wedge parts to return to normal will effectually retain the wedge in operative position upon the rail base.

When the several parts of my improved 90 rail anchor are in the positions illustrated in Figs. 1 and 2 with the bifurcated wedge 16 tightly fitted upon the base of its associated rail and disposed in the receptacle 15, the wedge will travel with the rail in 95 case of creeping, and so automatically lock the several parts together, the element 11 abutting against one of the ties upon which the rail is mounted serving to stop the creeping.

The several parts of my improved rail anchor are preferably constructed of malleable iron, although this is not necessarily the case. The wedge 16, however, should be

made of some material capable of being slightly distorted without danger of breaking when the wedge is forced upon the edge of the associated rail base, and the wedge should be capable of maintaining its grip upon the rail base after it has been driven into operative position.

The rail anchor above described is particularly advantageous inasmuch as expansion or contraction of the several parts due to changing temperature does not impair the reliability of the anchor inasmuch as the several parts tighten up into locking position when creeping takes place, even though the parts have expanded or contracted somewhat due to changing temperature. As a matter of fact, the expansion or contraction due to change in temperature of those parts of the anchor other than the bifurcated wedge is a great deal more than that of the wedge, so that the grip of the wedge upon its associated rail flange is not lessened any appreciable amount.

What I claim as new and desire to secure by Letters Patent of the United States is:—

1. A rail anchor comprising a body portion having formed integral therewith a tie-engaging arm and a clip arranged to engage one edge of a rail base, a tapered wedge arranged to engage three sides of the rail base on the side of the rail opposite said clip, said wedge being fixed with respect to the rail and arranged to creep therewith, and means formed integral with said body portion forming a receptacle for said wedge and provided with surfaces adapted to coact with said wedge.

2. A rail anchor comprising a body portion having formed integral therewith, a tie-engaging arm and a clip arranged to embrace one edge of a rail base, a tapered wedge arranged to embrace the edge of the rail base opposite said clip, said wedge arranged to engage the rail base with a driving fit so that said wedge will creep with the rail, and a receptacle for said wedge formed integral with the body portion of the rail anchor and having surfaces arranged to coact with said tapered wedge.

3. A rail anchor comprising a body portion, a tie-engaging element and a clip for embracing one edge of a rail base, a tapered wedge of substantially U-shaped cross-section arranged to embrace the edge of the rail base opposite said clip, said wedge being fixed with respect to the rail and arranged to creep therewith, and a receptacle for the wedge carried by the body portion and provided with surfaces coacting with said wedge.

4. A rail anchor comprising a body portion, a tie-engaging element, and a clip for embracing one edge of a rail base, a tapered wedge of substantially U-shaped cross-section

arranged to be driven upon the edge of the rail base opposite said clip, said wedge being fixed with respect to the rail and arranged to creep therewith, and a receptacle for the wedge carried by the body portion and provided with surfaces coacting with said wedge.

5. A rail anchor comprising a body portion provided with means for engaging one edge of a rail base, a tapered wedge of substantially U-shaped cross-section arranged to be driven to position upon the edge of the rail base opposite said engaging means and retained fixed thereon so that the wedge will creep with the rail, and means carried by the body portion arranged to embrace said wedge and provided with surfaces arranged to coact therewith.

6. A rail anchor comprising a body portion provided with means for engaging one edge of a rail base, a tapered longitudinally-bifurcated wedge arranged to embrace the edge of the rail opposite said engaging means, said wedge arranged to remain fixed with respect to the rail and to creep therewith, and means carried by the body portion adapted to embrace said wedge and provided with surfaces adapted to coact with the wedge.

7. A rail anchor comprising a body portion provided with a clip for engaging one edge of a rail base, a tapered longitudinally-bifurcated wedge arranged to be driven to position upon the edge of the rail base opposite said clip and held in fixed position embracing the edge of the rail base by the tendency of the wedge parts to return to normal, and a receptacle carried by the body portion arranged to embrace said wedge and having surfaces coacting therewith.

8. A rail anchor comprising a body portion having means for holding it stationary, and a bifurcated element arranged to be driven to position upon a rail base and held in fixed position by the tendency of the parts of the bifurcated element to return to normal, said bifurcated element and body portion provided with coöperating wedging surfaces.

9. A rail anchor comprising a body portion arranged to extend under the base of a rail and having a tie-engaging arm, and a tapered wedge of substantially U-shaped cross-section arranged to be driven to position upon an edge of the rail base and held in fixed position by the tendency of the wedge parts to return to normal, said body portion having a wedging surface coöperating with said tapered wedge.

10. A rail anchor comprising a body portion arranged to extend under the base of an associated rail and provided with a tie-engaging extension formed integral therewith, a clip formed integral with said body por-

tion arranged to embrace one edge of a rail base, a tapered wedge of substantially U-shaped cross-section arranged to be driven to position upon the edge of the rail base opposite said clip, said wedge being held in fixed position by the tendency of the wedge parts to return to normal, and a receptacle for said tapered wedge formed integral with

said body portion and provided with wedging surfaces coacting with said wedge. 10

In witness whereof, I hereunto subscribe my name this 26th day of May, A. D. 1914.

WILLIAM V. OSBORNE.
